COMBINED COUNTERSINK AND COUNTERBORE ATTACHMENT FOR TWIST DRILLS

Willard F. Wolff, Belvidere, N. J.

Application March 18, 1953, Serial No. 343,125

1 Claim. (Cl. 77—66)

1

This invention relates to tools and more particularly to a combined countersink and counterbore attachment for twist drills.

An object of this invention is to provide an attachment for twist drills whereby the hole formed by the drill may be formed either with a countersink recess or with a counterbore, the device including a gauge or that the recess or counterbore may be made to the desired depth.

Another object of this invention is to provide a combined countersink and counterbore attachment for twist drills which can be used with drills of various sizes.

A further object of this invention is to provide an attachment of this kind which is simple in construction and can be produced at small cost.

With the above and other objects in view, my invention consists in the arrangement, combination and details of construction disclosed in the drawings and specification, and then more particularly pointed out in the appended claim.

In the drawing—

Figure 1 is a detailed plan view of a combination countersink and counterbore attachment constructed according to an embodiment of this invention,

Figure 2 is a detailed side elevation of the device,

Figure 3 is a sectional view taken on the line 3—3 of Figure 2,

Figure 4 is a plan view, partly broken away and in section, of the inner side of one of the elements forming this device.

Referring to the drawing, the numeral 10 designates generally a conventional twist drill, and the numeral 11 designates generally an attachment which is adjustably mounted on the drill 10 and is adapted to form either a countersink or a counterbore in the material which is being drilled by the drill 10.

The attachment 11 comprises a pair of plates 12 and 13 which are of like construction and are disposed on opposite sides of the drill 10. These plates 12 and 13 are clamping plates and each plate is formed with a longitudinal channel 14 adapted to partly receive the drill 10 and hold the drill against rotary movement when clamped between the two plates 12 and 13.

The plate 12 has extending from one end thereof a countersink forming blade 15 and has extending from the opposite end thereof a counterbore forming blade 16. The blade 16 is formed with a projection 17 on the inner side thereof which is adapted to engage in a fluting 18 of the drill 10, as shown in Figure 2. Blade 15 is

2

also provided with a projection or extension 19 at the point of the blade which is engageable in a fluting 18. The plates 12 and 13 are tightly clamped upon the drill 10 by means of clamping screws 20, and a set screw 21 is threaded through plate 12 and bears against the periphery of drill 10.

In order to provide a means whereby the depth of the countersink or counterbore may be regulated, plate 12 is provided with a pair of longitudinal openings 22 and 23 which open through opposite ends of the plate 12. The shank 24 of a gauge member generally indicated at 25 is adapted to engage in a selected one of the openings 22 or 23 and in the present instance the shank 24 is mounted in opening 23 and is secured against movement therein by means of a set screw 26.

The outer end of the gauge member 25 is formed with an eye 27 which is adapted to bear against the outer side of the work so that the operator may determine the exact depth of either the counterbore or the countersink.

In the use of this device, where it is desired to counterbore the work the tool is mounted after the manner disclosed in Figures 1 and 2, with the blades 16 of the counterbore element projecting in the direction of the cutting end of drill 10. Gauge member 25 is set by adjustment of shank 24 in opening 23 so that the counterbore will be cut to the desired depth. Drill 10 is operated in the normal manner and when blades 16 contact with the work the work is counterbored about the opening formed by the drill 10.

Where it is desired to form a countersink in the work, the tool is reversed so that the countersink blades 15 will project in the direction of the cutting end of drill 10. Gauge member 25 is then reversed being placed in opening 22 so as to extend forwardly toward the countersink blade 15. As drill 10 cuts into the work blades 15 will form a countersink for the flat or tapered head of a screw or bolt when the drill enters the work to the depth of the countersink blades 15.

This attachment may be mounted on drill bits of varying sizes and can be readily adjusted along the length of the drills or drill bits so that a hole formed for a screw or bolt may be cut to the desired depth and the outer end of the hole formed either with a counterbore for receiving a washer, or a countersink for receiving the flat head of a screw.

I do not mean to confine myself to the exact details of construction herein disclosed, but claim

all variations falling within the purview of the appended claim.

What I claim is:

An attachment for twist drills comprising a pair of clamping plates engageable on opposite sides of a drill, each plate having a longitudinal channel on the inner face thereof in which a portion of the drill is adapted to engage, clamping screws for clamping said plates to the drill, a counterbore blade integral with and extending from one end of each plate, a countersink blade integral with and extending from the other end of each blade, and an inwardly extending projection carried by each blade engaging in a fluting

of the drill, one of said plates having a longitudinal bore therein, a gauge member slidably engageable in said bore, and means for securing said gauge member in a selected position relative to said bore.
